UNITED STATES PATENT OFFICE.

PAUL E. HAWKINSON, OF MINNEAPOLIS, MINNESOTA.

MULTIPLE SOCKET WRENCH.

1,407,860.

Specification of Letters Patent. Patented Feb. 28, 1922.

Application filed November 22, 1920. Serial No. 425,928.

To all whom it may concern:

Be it known that I, PAUL E. HAWKINSON, a citizen of the United States, residing at Minneapolis, in the county of Hennepin and 5 State of Minnesota, have invented certain new and useful Improvements in Multiple Socket Wrenches; and I do hereby declare the following to be a full, clear, and exact description of the invention, such as will 10 enable others skilled in the art to which it appertains to make and use the same.

My invention relates to improvements in wrenches and more particularly to multiple socket wrenches intended for general use 15 but especially adapted for use in connection with demountable wheel rims for turning the nuts or bolts of the rim-retaining lugs. As is well known, such nuts or bolts of standard rim-retaining lugs vary as to size 20 and, hence, different sized wrenches are required for turning the same. In tire or tire-repair stations, as well as garages, where a business is made of applying tire-equipped demountable rims to wheels and 25 removing the same therefrom, it is necessary to have a complete set or plurality of sets of socket wrenches to fit the nuts or bolts of standard rim-retaining lugs. Such wrenches are each formed with a brace by 30 which they may be operated and they are often misplaced so that considerable time is lost in finding a wrench of the required size and further, as the work of applying and removing demountable rims is to a very 35 large extent done in the sheet the mechanic is often required to make one or more trips into the building to get a wrench of the required size, resulting in considerable loss of time or he must borrow a wrench from 40 the driver of the car, which is very annoying.

To overcome this difficulty, I provide a single brace with a multiplicity of socket wrenches of the required sizes, any one of 45 which socket wrenches may be very quickly brought into an operative position, to fit the nuts or bolts of standard rim-retaining lugs or fastening devices.

To the above end, generally stated, the 50 invention consists of the novel devices and combinations of devices hereinafter described and defined in the claims.

Referring to the drawings:

Fig. 1 is a perspective view of the invention; and

Fig. 2 is a view principally in section taken on the line 2—2 of Fig. 1.

The numeral 3 indicates a brace having at one end a swiveled cap or head 4 and, at the other end, a fork 5. The intermediate or crank portion of the brace is provided with a rotatable hand piece 6. A head 7, having a multiplicity of radial arms 8, is rotatably mounted between the prongs of the fork 5 on nut-equipped bolts 9 secured in aligned bores in the ends of said prongs. Formed on the outer end of each arm 8 is a socket wrench 10, and the several wrenches 10 are of different sizes.

To hold the head 7 against rotation with 70 one of the wrenches 10 and its arm 8 aligned with the end of the brace 3, having the cap 4, there is provided a lever 11 intermediately fulcrumed to one of the prongs of the fork 5. This inner end of the lever 75 11 is expanded to afford a thumb piece 12 and has, at its other end, a pair of laterally spaced depending lugs 13, which straddle the prong of the fork 5 to which said lever is fulcrumed, and also releasably embraces 80 one of the arms 8.

A leaf spring 14 is anchored to the fork 5 under the lever 11 and yieldingly holds the thumb-piece-equipped end of said lever raised. By pressing downward on the 85 thumb piece 12, against the tension of the spring 14, the lugs 13 may be lifted to release the held arm 8 and thereby permit the head 7 to be rotated in the fork 4 to bring any one of the wrenches 10 into an 90 operative position in which it is aligned with said cap-equipped end of the brace 3. When the required wrench 10 is brought into an operative position, the head 7 is locked against rotation by releasing the lever 11 to permit the lugs 13 to embrace the arm 8 aligned with the fork 5. Obviously, the lugs 13, straddling one of the prongs of the fork 5, are held thereby 95 against lateral movement and, in turn, securely hold the head 7 against pivotal movement.

The above described invention, has in actual usage, proven highly efficient for the purpose had in view.

What I claim is:

1. A wrench of the kind described comprising a brace having a swiveled cap, a multiple arm head rotatively mounted on the brace, the arms of said head having nut 110

2
sockets of different sizes, and means for locking said head with one of the nut sockets substantially aligned with the cap and with another of said nut sockets substantially aligned with that portion of the brace to which it is pivoted.

- 5 2. A wrench of the kind described comprising a brace, a multiple arm head rotatably mounted on the brace, the arms of
10 said head having nut sockets of different sizes, and a yieldingly held lever mounted on the brace and having a pair of laterally spaced lock lugs embracing the brace and any one of the arms of said head.
- 15 3. A wrench of the kind described comprising a brace having at one end a swivelled cap and at the other end a fork, a multiple arm head rotatably mounted in the fork, the arms of said head having nut

20 sockets of different sizes, and means for locking said head with one of the nut sockets substantially aligned with the cap and with another of said nut sockets substantially aligned with the fork.

25 4. A wrench of the kind described comprising a brace having at one end a swivelled cap and at its other end a fork, a multiple arm head rotatably mounted in the fork, the arms of said head having nut sockets of different sizes, and a spring held 30 lock lever intermediately fulcrumed to the fork and having a lock detent engageable with any of the arms of the head for holding said head against rotation with one of the nut sockets substantially aligned with 35 the cap.

In testimony whereof I affix my signature.

PAUL E. HAWKINSON.
